DRAWBOLT

John B. Humphries, Stamford, Conn., assignor to The
Excelsior Hardware Company, Stamford, Conn.

Filed May 11, 1973, Ser. No. 359,343

Term of patent 14 years

Int. Cl. D8—07

U.S. Cl. D8—127

Fig. 1.

Fig. 2.

Fig. 3.

Fig. 4.

Fig. 5.

Fig. 6.

Fig. 7.

Fig. 8.

Fig. 9.

Fig. 10.

Fig. 11.

Fig. 12.

FIG. 1 is a top view of one embodiment of the drawbolt of my design;

FIG. 2 is a side view of the drawbolt of FIG. 1;

FIG. 3 is an end view of the drawbolt of FIG. 1;

FIG. 4 is a bottom view of the drawbolt of FIG. 1;

FIG. 5 is a view of the side opposite that of FIG. 2;

FIG. 6 is an end view opposite that of FIG. 3;

FIG. 7 is a top view of another embodiment of the drawbolt of my design;

FIG. 8 is a side view of the drawbolt of FIG. 7;

FIG. 9 is an end view of the drawbolt of FIG. 7;

FIG. 10 is a bottom view of the drawbolt of FIG. 7;

FIG. 11 is a view of side opposite that of FIG. 8; and

FIG. 12 is an end view opposite that of FIG. 9.

I claim:

The ornamental design for a drawbolt, substantially as shown and described.
